HOWARD C. DAVIS, OF ELIZABETH, AND WILLIAM H. THOMPSON, OF CHATHAM, NEW JERSEY, ASSIGNORS TO DAVIS ENGINEERING CORPORATION, A CORPORATION OF DELAWARE

HEAT EXCHANGER

Application filed June 29, 1929. Serial No. 374,625.

In straight tube heat exchangers, the elements are subjected to frequent changes in temperature which cause them to expand and contract. This expansion and contraction of the elements of the heat exchanger, unless properly compensated, causes leakage either between the elements, permitting the heating medium to mix with the heated medium, or from the heating or heated chambers to the atmosphere. In general, leakage in heat exchangers occurs between the tubes and the tube sheet as a result of the strains set up by the expansion and contraction of the tubes. Heretofore, it has been the general practice to compensate for the expansion and contraction of the tubes by some form of floating joint between the tube sheet and the casing. The floating joint, however, after use, commonly becomes worn and leakage occurs between the tube sheet and the casing.

In accordance with our invention, we construct a heat exchanger in which the elements are free to expand and contract with changes in the temperature without setting up strains that produce leakage. We employ a construction in which the tube sheets may be rigidly secured to the casing, the arrangement of tubes being such that one end of the tubes is free to move longitudinally.

Among the characteristics of our invention is the fact that the arrangement of the tubes and the proportioning of the area thereof produces a high velocity in the heat conducting medium for sweeping the condensate off of the heating surface, thereby maintaining its heat transfer efficiency.

Another feature of our invention is an arrangement of baffles that insures a cross flow, and maintains a uniform pressure drop throughout the length of travel of the liquid.

Specifically, we employ a casing made up of two parts, separable near one end thereof, each part being closed at its outer end with a suitable head. Near one end of the casing, a tube sheet is rigidly secured to the inner surface thereof. A second tube sheet, spaced a short distance from the first tube sheet, is secured between the two parts of the casing and forms with the first tube sheet a condensate chamber. A set of strategically located

tubes are secured at one end in the second tube sheet and extend longitudinally of the casing, the end opposite the tube sheet being closed or plugged. Tubes of a second set of a lesser diameter are secured in the first tube sheet and extend into and along the tubes secured in the second tube sheet, the inner tubes ending at a point adjacent the plugs in the ends of the outer tubes. The heat conducting medium is introduced into the chamber in front of the first tube sheet, enters the tubes of lesser diameter, flows along the tubes to the end thereof, and is returned through the outer tubes to the condensate chamber formed between the tube sheets from which it has an outlet. The area of the inner and outer tubes is so proportioned that the fluid in returning through the outer tube is given a high velocity and sweeps the condensate off of the inner surface of the tubes and thereby maintains their heat transfer efficiency. The fluid to be heated is admitted to the casing just beyond the second tube sheet and by a series of baffles is forced to take a cross flow back and forth transversely of the casing to the end thereof in which there is a suitable outlet.

The inner tubes are desirably centered in the outer tubes. We accomplish this centering of the inner tubes by providing a tapering strap which is secured over the remote end of the inner tube. This strap also serves to guide the inner tubes into and along the outer tubes in the assembly of the mechanism.

The baffles are spaced in accordance with the change in the viscosity of the fluid to be heated so that there will be a uniform pressure drop in the heated fluid throughout its travel through the exchanger.

Our invention comprehends other features and advantages which will hereinafter more particularly appear.

We shall now describe one embodiment of our invention in connection with the accompanying drawings in which:

Fig. 1 is a longitudinal sectional elevation taken along the center line of a heat exchanger embodying our invention;

Fig. 2 is a transverse section of the same taken on the line 2—2 of Fig. 1;

Fig. 3 is a transverse section of the same taken on the line 3—3 of Fig. 1, and

Fig. 4 is a longitudinal and end elevation of the end of an inner tube showing the centering strap thereon.

For the purpose of illustrating our invention, we have shown it as embodied in an oil preheater. It is to be understood, however, that it is by no means limited to such use. The exchanger comprises a casing made up of two parts—1 and 2—separable near one end thereof. A tube sheet 3 having suitable packing 4, on either side thereof, is secured between flanges 5 and 6 by means of which the two parts of the casing 1 and 2 are secured together. Adjacent the head 7 of the part 1, a second tube sheet 8 is secured to the inner surfaces of the casing in sealing relation therewith. Tubes 9 are secured in the tube sheet 3 and extend along inside of the casing parallel to the longitudinal axes thereof, to a point adjacent the head 10 of the part 2. The ends of the tubes adjacent the head 10 are effectively sealed by plugs 11 which are desirably welded therein. Tubes 12, of lesser diameter than the tubes 9, are secured at one end in the tube sheet 8 and extend into the tubes 9 to a point adjacent the plugs 11.

The tubes 12 are provided at the end adjacent the plugs 11 of the outer tubes 9 with rods 13 forming tapered straps adapted to center the tubes 12 within the tubes 9. These straps 13 project beyond the ends of the tubes 12 in substantially the shape of a V, the sides of this V having end portions extending along the sides of the end portion of the tube 12 and secured thereto, so that thereby the inner tube 12 will be guided into and along the inside of the outer tube 9 in effecting assembly, as well as also serving to center these tubes.

Strategically located spacers 14 serve to keep the baffles in spaced relation so as to reduce the frictional resistance to the cross flow of the heated medium. The spacers 14 to which the baffles are secured are secured at one end to the tube sheet 3 and at the opposite end to a plate 15 adjacent the ends of the outer tubes 9. The plate 15 is secured to the ends of the tubes by bolts 16 engaging threaded openings in the plugs in the end of the spacing tubes 14, the fluid carrying tubes 9 not being secured to this plate 15.

A series of baffles 17 are located within the casing and produce a back and forth transverse flow of the heated fluid through the casing. Successive baffles have a short segmental portion cut away near diametrically opposite sides of the casing. The baffles are spaced in accordance with the change in viscosity of the heated fluid as it flows through the exchanger. In the exchanger

illustrated, which is adapted for preheating oil, the distance between the baffles near the oil inlet is greatest, and decreases as the oil is heated and the viscosity lessened.

In the periphery of the casing, near the flange 6 of the section 2 thereof, an oil inlet 18 is provided. The first of the series of baffles 17 is placed adjacent the inlet so that as the oil enters, it flows across the tubes to the diametrically opposite side of the casing, through the cut-away segmental portion of the baffle, back across the tubes, and so on to the end of the casing where there is a suitable outlet 19 provided in the head 10. A steam inlet 20 is provided in the head 7 of the section 1. The steam entering the inlet 20, enters the tubes 12 extending through the tube sheet 8, proceeds along the tubes 12 to the end thereof, and is discharged into the outer tubes 9 returning along the outer tubes to be discharged into the condensate chamber formed between the tube sheets 3 and 8. Adjacent the tube sheet 8 there is a condensate outlet 21 provided in the wall of the casing.

By virtue of the fact that the tubes are free at one end they may expand and contract with the changes in temperature without setting up strains that would cause leakage either between the tubes and the tube sheet 95 or between the tube sheet and the casing. The tubes 12 expand within the tubes 9, and the tubes 9 and the spacers 14 which carry the plate 15 expand independently. By this arrangement the possibilities of leakage caused by strains set up from the expansion and contraction of the elements of the exchanger, or due to fatigue of material, by alternately setting up stresses and strains therein, is avoided.

It is obvious that various changes may be made in the embodiment shown in the drawings and above particularly described within the principle and scope of our invention as expressed in the appended claims.

Claims:

1. A heat exchanger comprising a casing having inlet and outlet openings therein, a tube sheet adjacent one end of said casing having openings therethrough, a second tube sheet in the rear of said first mentioned tube sheet having openings therethrough of greater diameter than and in alignment with the openings in said first tube sheet, tubes extending longitudinally of said casing secured in said tube openings, the tubes secured in the openings of said first mentioned tube sheet extending within the tubes secured in said second mentioned tube sheet, and means for centering the tubes secured in the first mentioned tube sheet in the tubes secured in said second mentioned tube sheet, said means including tapering guides projecting beyond the ends of the inner tubes.

2. A heat exchanger comprising a casing

- having inlet and outlet openings therein, a tube sheet adjacent one end thereof having openings therethrough, a second tube sheet in the rear of said first mentioned tube sheet having openings therethrough in alignment with and of greater diameter than the openings in said first tube sheet, and tubes extending longitudinally of said casing secured in said openings, the tubes secured in the openings in said first mentioned tube sheet extending within the tubes secured in said second mentioned tube sheet and having tapered guide straps on the end thereof remote from the tube sheet, said guide straps being substantially V-shape with their end portions extending over and their tapered middle portions projecting beyond the ends of the tubes so as to form both guiding and centering means, the ends remote from the tube sheet of the tubes secured in said second tube sheet being sealed, said casing having an inlet in advance of said first mentioned tube sheet and an outlet between said tube sheets, said casing also having another inlet just beyond said second tube sheet and another outlet from the remote end of the casing.
3. A heat exchanger comprising a two part casing separable near one end thereof, a tube sheet having openings therethrough secured between the parts of said casing, a second tube sheet secured to the inner wall of said casing in advance of said first mentioned tube sheet having openings therethrough of lesser diameter than and in alignment with the openings in said first tube sheet, tubes extending longitudinally of said casing secured at one end in the openings in said tube sheets, the tubes secured in said second tube sheet extending within the tubes secured in said first mentioned tube sheet; a series of baffles transverse to said casing to create a cross flow of the fluid to be heated, and spacers to which the baffles are secured extending longitudinally of the casing for maintaining the baffles in spaced relation, said spacers being secured at one end to said first mentioned tube sheet.
4. A heat exchanger comprising a two part casing separable near one end thereof, a tube sheet having openings therethrough secured between the parts of said casing, a second tube sheet secured to the inner wall of said casing in advance of said first mentioned tube sheet having openings therethrough of lesser diameter than and in alignment with the openings in said first tube sheet, tubes extending longitudinally of said casing secured at one end in the openings in said tube sheets, the tubes secured in said second tube sheet extending within the tubes secured in said first mentioned tube sheet and having tapered straps on the ends thereof remote from the tube sheet, a series of baffles transverse to said casing to create a cross flow of the fluid to be heated, and spacers extending longitudinally of the casing for maintaining the baffles in spaced relation, said spacers being secured at one end to said first mentioned tube sheet and at the other end to a plate adjacent against the ends remote from the tube sheet of the tubes secured in said first mentioned tube sheet.
5. A heat exchanger comprising an enclosing casing, a tube sheet extending across the casing to form an end chamber adjacent one end thereof, a second tube sheet extending across the casing in spaced relation with the first tube sheet to form a second end chamber in the other end portion of the casing and an intermediate chamber between said tube sheets, a set of tubes supported by and opening through said second tube sheet into the intermediate chamber and extending longitudinally within the second end chamber and closed at their ends remote from said second tube sheet, a second set of tubes supported by and at their adjacent ends opening through said first tube sheet, said second set of tubes extending across the intermediate chamber and longitudinally into and along the tubes of the first set into which they open at their remote ends, a series of transverse longitudinally spaced baffles in the second end chamber, and longitudinally extending spacers for said baffles secured at one end to the second tube sheet for thereby supporting the baffles, an inlet and an outlet being provided for passing a fluid from one end to the other through the second end chamber, and another inlet and another outlet being provided for independently passing another fluid through the other two said chambers and to include the passage of this latter fluid through the said two sets of tubes from one of these latter chambers to the other.
